(57) **CLAIM**

The ornamental design for a video converter, as shown and described.

DESCRIPTION

FIG. 1 is top, front perspective view of a video converter showing our new design;

FIG. 2 is a top, rear perspective view thereof;

FIG. 3 is a front plan view thereof;

FIG. 4 is a top plan view thereof;

FIG. 5 is a rear plan view thereof;

FIG. 6 is a bottom plan view thereof;

FIG. 7 is a right side view thereof; and,

FIG. 8 is a left side view thereof.

The broken lines are for the purpose of illustrating portions of the video converter and form no part of the claimed design.
